UNITED STATES PATENT OFFICE.

AMELIA B. WELLS, OF NEW YORK, N. Y.

DESIGN FOR A LADY'S DRESS.

54,491.

Specification for Design.

Patented Feb. 10, 1920.

Application filed October 18, 1918. Serial No. 258,763. Term of patent 7 years.

To all whom it may concern:

Be it known that I, AMELIA B. WELLS, a citizen of the United States, residing at New York city, in the borough of Manhattan, county and State of New York, have invented a new, original, and ornamental Design for a Lady's Dress, of which the following is a specification, reference being had to the accompanying drawing, forming part thereof.

I claim:

The ornamental design for a lady's dress as shown.

AMELIA B. WELLS.
